UNITED STATES PATENT OFFICE.

MAURICE H. MANDELBAUM, OF CHICAGO, ILLINOIS.

COIN-REGISTER.

1,243,619.

Specification of Letters Patent. Patented Oct. 16, 1917.

Application filed February 3, 1913. Serial No. 745,765.

To all whom it may concern:

Be it known that I, MAURICE H. MANDELBAUM, a citizen of the United States, and resident of Chicago, in the county of Cook and State of Illinois, have invented certain new and useful Improvements in Coin-Registers, of which the following is a specification.

This invention relates to coin registering mechanism involving what I believe to be a novel principle of operation.

In all registering mechanism with which I am familiar, particularly that class where coins are inserted within the mechanism, registration is effected either by the dropping of the coin or by the manipulation of some member necessarily operated as a part of the use of the instrument to effect registration.

In my construction, which relates particularly to coin registers, the coins may be deposited and the instrument relieved of all its functions, this without actuating the register mechanism, the latter being effected only as and when the coin is withdrawn and the construction being such that it is impossible to withdraw a coin without actuating the register.

This new principle of construction enables the use of register mechanisms where a coin or token is employed in a great many situations where such use was impractical. As for example, in coin operated registers used in telephones of a certain class, the operator must be provided with a coin of a designated size or with a token and the operation of using the telephone effects the registration. In certain classes of fare registers also the passenger deposits a coin in the register and the insertion of the coin actuates the register mechanism.

In my device the coins may be inserted to any number, within a suitable receptacle, and the register mechanism remains unaffected until the coins are withdrawn which they may be by the user or custodian of the instrument at any time, the registration being effected by the fact that upon each withdrawal the registering mechanism is actuated and therefore settlement must be made according to the record thus produced.

I have designed as illustrative of my device a simple form of mechanism comprising a locked receptacle which may be a fare register, a register box for an automatic telephone, or any of a plurality of other de-

vices of this sort and which comprises essentially only a coin receptacle, a registering mechanism comprising register wheels and an actuating key which effects the discharge of the coins one at a time and at the same time and simultaneously actuates the register.

My invention will be more readily understood by reference to the accompanying drawings, wherein,

Figure 1 is a vertical section through a coin receptacle and ejecting mechanism such as contemplated by me;

Fig. 2 is a similar view showing a portion of the registering mechanism;

Fig. 3 is a plan view partly in section of the construction shown in Fig. 2;

Fig. 4 is a transverse vertical section;

Fig. 5 is a detail end elevation of the register mechanism.

Referring more particularly to the drawings, it will be seen that in one embodiment of my invention I provide a receptacle 10, having a closure 11, which may be locked or sealed if desired. Within this receptacle I mount the registering and receiving mechanism hereinafter more fully described.

The receptacle may be provided with a handle 12, in case the device is to be used by a street railway conductor. In other applications of the device the box may be mounted on a wall or used in any other desirable manner.

Projecting through the top wall of the box is a tube 13, having a closed top and provided with a slot 14, through which the coins may be inserted. This slot may be protected by a spring 15, to prevent the removal of the coins therethrough. The bottom of the tube is notched as at 16, the notch occupying a space equal to the width of the coin to be removed therethrough. The tube rests on a support 17, on which the coins in the tube also rest. The means for ejecting the coins from the tube may consist of an ejector 18, pivoted at 19, and arranged for limited oscillation against a coil spring 20. This ejector is pivoted to a plunger 21, mounted in suitable ways 22, carried by a frame 23, supported in the receptacle 10, on the standards 24. This plunger 21 is normally held in retracted position by means of a coiled spring 25. The plunger rests on the roller bearings 26, by means of which frictional resistance is largely eliminated. The means for causing the forward movement of

100

110

the plunger 21, is the key-actuated vertical plunger 27, having a triangular head 28. This plunger is normally held in raised position by means of a spring 29, and is surrounded by a key 30. This plunger is guided in a pair of cross pieces 31, against the lower face of the bottom of which the notch 32 of the head rests when the plunger is in raised position. The triangular point 28 extends into the slot 33, formed in the plunger 21, the diagonal face of the vertical plunger normally resting against a roller 34. It will be seen that when the key 30 is depressed, the plunger 21 is advanced carrying with it the ejector 18, which ejector normally is seated behind the coin 35, in the bottom of the tube 13. Thereby the coin is ejected and falls to the floor of the receptacle 10.

20 As a means for registering the number of coins ejected from the tube 13, and also as a means for preventing the accidental displacement of any such coins I provide a rocker 36, pivoted at 37, to the cross piece 17, and provided with a lug 38, projecting into the plane of the tube 13, and lying in the notched portion 16 thereof. Thus a coin may not be ejected from the tube without displacing the lug 38 and rocking the arm 36. 25 The opposite end of the arm 36 has pivoted thereto a link 39, connected to a rocker 40, pivoted at 41 to a bracket 42, secured to a portion of the frame 23. One arm of the rocker 40 projects into an opening in a lever 35, best shown in Fig. 5, which lever is mounted for oscillation on a shaft 44, which shaft carries number wheels 45, 46, constituting the registering mechanism. Also carried on the shaft 44, is a ratchet wheel 47, 30 with which a pawl 48, pivoted to the lever 43 cooperates. The pawl is held in engagement with the ratchet by means of an expansion spring 49. It will be seen that by the ejection of a coin from the tube 13, the rocker 36 is moved, thus transmitting motion to the link 39, rocker 40, lever 43 and ratchet 47. Thus motion is transmitted to the number wheels, which wheels may be of any usual or well known construction. The 35 top wall of the receptacle 10 is provided with a window 50, as shown in Fig. 2, directly over the number wheels by means of which the amounts set up on the wheels may be determined.

40 In the use of the illustrated device in connection with street cars, it is contemplated that the passenger shall insert the proper coin in the slot 14. These coins may, if desired, be displaced by the conductor by operating the key 30, the coins falling into the receptacle 10. However, as each coin is ejected from the tube it is registered on the number wheels. When the conductor's box is turned in to the auditor, the coins cannot 45 be removed from the tube by him except

by actuating the key-operating registering mechanism. Thus, after the fare is collected from the passenger, there is no means for removing the coin from the box without registering the same. It will be noted that if no coins are in the tube 13, the key may be reciprocated freely without actuating the registering mechanism.

70 As distinguished from ordinary change making machines wherein a given amount of change may be obtained from the machine while the machine indicates the amount of such change, in connection with which the coins are simply stacked in tubes or compartments, by the user of the machine, and may as readily be withdrawn from such tubes or compartments, I believe I am the first in the art to provide a collecting device into which the predetermined coin, as car-fare, telephone-toll, sale-prices, as in a five and ten cent store, may be introduced, through a suitable inlet, but cannot be withdrawn through said inlet, so that the collected coins can only be obtained from the machine through a discharge apparatus adapted to 75 register the various operations of the discharge, so that while the contents of the collector are available to its custodian, for example, the salesman in making change to give the customer, the proper coin for deposit in the collector, there will, however, be a progressive fixed registration of the total amount discharged from the machine so that the amount to be turned in to the proprietor is always shown by the register, plus 80 the remaining contents of the machine, the more convenient method of transacting the business being for the salesman to discharge from his own device the contents thereof 85 completely, and turn in the full amount indicated by the register of the machine devoted to his personal use.

100 It will be obvious that the application of the device herein described is only one of many which might be suggested. Therefore 110 I do not wish to be limited to the exact structure herein shown and described.

I claim:

115 A device of the character described consisting of a portable coin collector and counter including a coin receiving and storing chamber adapted to receive and store a stack of coins of a given denomination, said chamber being formed with a guarded inlet through which the coins may be freely inserted into the chamber at will but out of which said coins are permanently prevented from withdrawal, a predetermined normally closed emergent discharge opening for said 120 storing chamber, a handle whereby the device may be conveniently held in one hand of the user, emergent discharge instrumentalities operatively associated with the coin discharge opening having a thumb actuatable means to be operated from the hand carry- 125

ing the device for ejecting a single coin at a time from the storage chamber at the desire of the user and at a point accessible to the other hand of the user, and a coin counter 5 adapted to be actuated by the releasing of each coin from the chamber to progressively count and indicate the total number of coins

taken from the chamber and which added to the coins remaining in the chamber will denote the grand total of coins collected.

MAURICE H. MANDELBAUM.
